INVENTOR.

UNITED STATES PATENT OFFICE.

RALPH C. THOMPSON, OF ATTLEBORO, MASSACHUSETTS.

DESIGN FOR A BADGE.

40,456.

Specification for Design.

Patented Jan. 25, 1910.

Application filed June 10, 1909. Serial No. 501,430. Term of patent 3½ years.

To all whom it may concern:

Be it known that I, RALPH C. THOMPSON, a citizen of the United States, residing at Attleboro, in the county of Bristol and State of Massachusetts, have invented a new, original, and ornamental Design for a Badge, of which the following is a specification, reference being had to the accompanying drawing, forming part thereof.

The figure is a front elevation showing the design of the badge.

I claim:

The ornamental design for a badge, as herein shown.

RALPH C. THOMPSON.

Witnesses:

RALPH C. ESTES,
HELEN DUMICAN.
